MACHINE FOR APPLYING FASTENERS TO
WEB MATERIALCarl H. Lofgreen, New York, N. Y., assignor to
Equitable Paper Bag Co. Inc., Long Island City,
N. Y., a corporation of New York

Application April 26, 1946, Serial No. 665,251

18 Claims. (Cl. 218—15)

1

This invention relates to a machine for applying fasteners of the button or washer type to a continuously moving web of material. The web thereafter may be cut and folded to form envelopes and these fasteners are then used in connection with string attaching means to close the envelope flaps.

An object of the invention is to provide a machine of this character in which an endless web of paper or other suitable material may have such fasteners applied along the edge thereof at predetermined intervals. A fastener of this type usually consists of a perforated disc or washer which lies on one face of the web and a reinforcing member which lies on the opposite face of the web, the two being secured together and to the web by a riveted eyelet.

The machine is so arranged with respect to the paper web to which the fasteners are to be applied that the guided edge of the web passes between a pair of co-planar, rotary combination pick-up and riveting members or arms. One of these riveting arms has means thereon adapted to pick up a washer into whose perforation an unriveted eyelet has previously been inserted. The eyelet at that time has a headed end and an unheaded end. The other of the arms has means thereon adapted to pick up a reinforcing member which has been previously perforated and then cut to size from strip material which may be appropriately fed into the machine for such purposes. The two arms are mounted on independent shafts and are rotated in synchronism so that once during each revolution of these arms, they come in to register on opposite sides of the web. When in register the washer carried on one arm and the reinforcing member carried on the other arm are in alignment on opposite sides of the web and the unheaded portion of the eyelet carried by the washer pierces the web and receives the reinforcing member. The unheaded end is then peened or bent over by an anvil part on the arm carrying the reinforcing member, thereby securing the washer and reinforcing member to the web on opposite sides thereof. The web moves continuously and its surface speed is kept the same as that surface speed of the operating ends of the co-planar rotary arms at the time that the latter become aligned for the fastening operation just described. The united washer and reinforcing member are released by the respective pick-up means and move away from the machine with the web.

Means are provided in the machine to feed the perforated washers one by one from a supply source to a point at which an eyelet having an

2

unheaded end and a headed end is inserted into the washer perforation and thereafter to move such washer-eyelet combinations one by one to a pick up point where such combinations may be picked up successively by the pick-up means of one of the said rotating arms. Means are also provided in the machine for feeding the said eyelets from a hopper to the said point at which they are combined with the successive washers.

10 Means are provided at said point for inserting the eyelets into said washers as just described.

Means are also provided in the machine for shearing reinforcing members from a roll of strip material to proper size, for perforating each reinforcing member prior to its severance from the strip and for delivering the perforated reinforcing member to a pick-up point at which it may be picked up by the pick-up means of the other of the two co-planar rotary arms, and then 15 carried by the latter pick-up means for union with the web and the washer. Means are also provided in the machine for synchronizing the operation of various movable parts thereof so that a washer-eyelet combination and a reinforcing member will be delivered once during each revolution of the respective co-planar arms to the appropriate pick-up means of the latter for union with the web.

A principal object of the invention is to provide 20 a unitary machine capable of effecting the foregoing union of washers and reinforcing members with the moving web at spaced-apart points.

A further object of the invention is to provide 25 a machine that may be operated continuously and rapidly so that washers and reinforcing members constituting the fasteners may be applied to a moving web of sheet material on a mass production basis.

Still another object of the invention is to provide 30 means for synchronizing the operation of various of the movable parts of the machine so that a complete cycle of operations occurs once during each revolution of the co-planar rotary arms.

45 A further object of the invention is to provide novel means for combining each perforated washer with an eyelet having a headed end and an unheaded end prior to their union with the moving web and a reinforcing member.

50 Yet another object of the invention is to provide novel means for preparing perforated reinforcing members or reinforcements in the machine prior to the union of each such reinforcement with a washer and the moving web.

55 To the accomplishment of the foregoing and such other objects as may hereinafter appear,

this invention consists in the novel construction and arrangement of parts hereinafter to be described and then sought to be defined in the appended claims, reference being had to the accompanying drawings forming a part hereof, which show, merely for the purposes of illustrative disclosure, a preferred embodiment of the invention, it being expressly understood, however, that changes may be made in practice within the scope of the claims without disengaging from the invented idea.

In the drawings in which similar reference characters denote corresponding parts and in which sectional views are seen in the direction of the arrows on various of the section lines:

Fig. 1 is a front elevational view of the machine;

Fig. 1a is an enlarged fragmentary section taken along line 1a—1a of Fig. 2 illustrating a detail of the washer feeding mechanism;

Fig. 2 is a partial end elevational view of the machine seen from the right hand side of Fig. 1;

Fig. 3 is a partial end elevational view of the machine seen from the left hand side of Fig. 1;

Fig. 4 is a partial vertical section taken along line 4—4 of Fig. 1 and illustrating a part of the mechanism used for operating the reinforcement delivery means;

Fig. 5 is a partial vertical section taken along line 5—5 of Fig. 1 and illustrating a part of the strip feeding mechanism;

Fig. 11 is a partial longitudinal and vertical section taken along line 11—11 of Fig. 2 and illustrating parts constituting the washer feeding mechanism, the means for combining such washers with eyelets, the washer-eyelet combination receiving and positioning means and the mechanism for transferring such combinations to the latter means;

Fig. 12 is a fragmentary section similar to that of Fig. 11 showing parts thereof in a different position of operation;

Fig. 13 is a section similar to Fig. 11 showing some of the parts thereof in still another position of operation;

Fig. 14 is an enlarged rear elevational view of the co-planar pick-up and riveting arms that serve for uniting the washers, the reinforcements and the eyelets with the moving web, the two arms being shown in aligned or uniting position;

Fig. 15 is a vertical sectional view taken along lines 15—15 of Fig. 14;

Fig. 16 is a vertical sectional view taken along lines 16—16 of Fig. 15;

Fig. 17 is an elevational view of the lowermost co-planar arm seen from the right of Fig. 16;

Fig. 18 is a diagrammatic illustration of the co-planar arms and their respective positions relative to the moving web just prior to the union of the washer, reinforcement and eyelet with the web;

Fig. 19 is a similar diagrammatic view of these arms at the moment of union;

Fig. 20 is a fragmentary partial plan and sectional view of the terminal or delivery end of the eyelet feeding mechanism showing the position of parts just prior to the insertion of an unriveted eyelet into one of the washers;

Fig. 21 is a partial vertical section and elevational view taken along lines 21—21 of Fig. 20;

Fig. 22 is a fragmentary view similar to that of Fig. 20 showing the position of parts when an unriveted eyelet has been inserted into one of the washers;

Fig. 23 is a partial vertical section and elevational view taken along lines 23—23 of Fig. 22;

Fig. 24 is a fragmentary view similar to those of Figs. 20 and 22 showing a position of parts intermediate those of Figs. 20 and 22;

Fig. 25 is a partial vertical section and elevational view taken along lines 25—25 of Fig. 24;

Fig. 26 is a partial vertical section taken along lines 26—26 of Fig. 1 and illustrating a part of the mechanism for inserting unriveted eyelets into the washers, and its operating elements;

Fig. 27 is a partial vertical section and elevational view taken along lines 27—27 of Fig. 1 and illustrating means for oscillating the eyelet feeding mechanism;

Fig. 28 is an enlarged partial transverse vertical section of the upper end or receiving end of the eyelet feeding mechanism and includes the eyelet containing hopper and associated mechanism for delivering the unriveted eyelets to the eyelet feeding mechanism;

Fig. 29 is an elevational view of said upper or receiving end of said eyelet feeding mechanism viewed from the right of Fig. 28 with the hopper removed;

Fig. 30 is a sectional view taken along lines 30—30 of Fig. 29 and illustrating an eyelet delivered to the receiving end of the eyelet feeding mechanism; and

Fig. 31 is a fragmentary plan view of an envelope made from a part of a web to which washers, eyelets and reinforcements have been applied at regular intervals on the machine.

The machine of this invention can be subdivided into a number of elements or units, namely, (1) a uniting unit in which the washers C, reinforcement members R and eyelets E are united with the traveling paper web W by means on the co-planar arms, (2) a reinforcement forming and feeding unit, wherein perforated reinforcements R are severed from a strip S of reinforcement material and delivered to a point for pick-up by parts of the uniting unit, and (3) a washer and unriveted eyelet feeding unit in which the washers C and unriveted eyelets E are combined and delivered to a point for pick-up by parts of the uniting unit.

The washers C generally are perforated and circular in plan and are made of stiff paper or other suitable material. The unriveted eyelets E are tubular and have a headed end and an unheaded end. The reinforcements R are perforated centrally and may have any desired shape in plan view. Herein they are shown as of square or rectangular shape. The strip S from which

they are formed in the machine is stiff paper or other suitable material.

The uniting unit

Referring to the drawing and first to Figs. 1, 2, 3 and 14-18 inclusive, 10 denotes frame parts. A main drive shaft 11 is rotatively supported in bearings 12 carried by the frame parts 10. A driving member such as sprocket wheel 13 is secured to the drive shaft 11. A spur gear 14, likewise, is secured to this drive shaft 11.

The drive shaft 11 projects outwardly of a frame part 10 and one of the rotary co-planar arms or members 15 is secured to this portion of said shaft 11, for example by the locking bolt 16 (Fig. 15). The arm 15 constitutes the washer and unriveted eyelet carrying arm.

This arm 15 has a longitudinally extending bore 17 (Fig. 15) in which a tubular sleeve 18 is mounted. This sleeve 18 projects outwardly of the operating end of arm 15 and its end 18a serves as a seat for the headed ends of the unriveted eyelets E as will be presently described. The inner end of the sleeve bears against the annular abutment or shoulder 19. A spring actuated plunger 20 is slidably guided in the sleeve 18 and in an extension 17a of bore 17. This plunger has a pointed or centering end 21 which normally is urged outwardly of the sleeve end 18a by the spring 22. The fixed collar 23 on the plunger 20 and the abutment or shoulder 19 limit such outward movement. A member 24 is attached to the plunger 20 and extends outwardly of the arm 15 through a slot 25 terminating in a cam follower 26 for a purpose presently to be described.

A slide member 30 (Figs. 14 and 16) is carried on a longitudinal face of the arm 15. This member has longitudinally extending slots 31 so that it can be guidedly moved longitudinally over the said face of said arm relative to the attaching members or pins 33 which are secured to the arm 15 and which extend through these slots 31. A pair of pick-up claws 35, 36 (Figs. 1, 17 and 14-16) are pivotally supported at 37, 38 (Figs. 1 and 17) from the slide member 30. Springs 39, 40 tend to rotate these claws toward each other about their pivotal supports 37, 38. The pick-up claws 35, 36 have oppositely facing cam surfaces 35a, 36a which cooperate with a cam pin 41 carried by the arm 15 which projects through a slot 42 in the slide member 30. The slide member 30 normally is urged by a spring 43 in a direction away from operating end K of the arm 15. The opposite ends of the spring 43 are attached respectively to a member 44 fixed to the slide 30 and to a member 45 fixed to the arm 15. The movement of slide member 30 toward the operating end K of arm 15 and counter to the action of spring 43 is effected by a crank lever 48, one of whose ends is pivotally secured at 49 to a flange 50 extending from the slide member 30. The other end of the lever is fixed to a shaft 51 rotatably supported from flange parts 52 of the arm 15. A second crank lever 53 is fixed to the shaft 51. A cam follower or roller 54 is rotatably secured to this lever 53 for purposes presently to be described.

The cam pin 41 is so positioned relative to the cam faces 35a, 36a of the claws 35, 36 that in the retracted position of the spring 43, as shown in Fig. 17, these claws 35, 36 are spread apart with their overhanging ends 35b, 36b clear of the operating end K of arm 15 (Figs. 15 and 16). This is the release position of the claws 35, 36. On the

other hand, when the slide member 30 is moved longitudinally toward the operating end K of the arm 15 under action of the cam follower 54 and crank levers 53 and 48, the high portions of the said cam surfaces 35a, 36a clear the pin 41 thus permitting the springs 39 and 40 to rotate the claws 35, 36 toward each other to the limit permitted by the high portions of the cam surfaces 35a, 36a. In the latter position, the overhanging ends 35b, 36b of the claws overlie the operating end K of the arm 15 respectively on opposite sides of the plunger entering end 21 for purposes presently to be described. This is the position of these claw ends 35b, 36b when they act to pick a washer and unriveted eyelet combination from the end of the washer and eyelet assembly unit and carry it toward the uniting position of the arm 15.

A cam 58 (Figs. 1, 3 and 6) is secured adjustably to a frame part 10 about the shaft 11. The cam follower 54 which serves to reciprocate the slide member 30 on the arm 15 operates on the outer surface of this cam 58. The latter in addition has a face cam surface 58a on which the cam follower 26 of the plunger 20 operates (Figs. 1, 3, 6, 14 and 15).

In each revolution of the shaft 11, the cam 58 actuates the cam follower 54 as follows: Starting from a point in the orbital travel of the operating end K of the arm 15 just beyond its uppermost or uniting or 12 o'clock position in the clockwise direction of rotation of Figs. 3 and 6 at which time the spring 43 has retracted the slide 30 to its furthermost point away from the operating end K of arm 15, the cam 58 moves the follower 54 to shift the slide 30 outwardly toward said operating end K and the slide reaches its extreme outermost position just prior to the arrival of said operating end K at its lowermost or pick-up or 6 o'clock position. In this period the cam claw surfaces 35a, 36a are forced away from the cam pin 41 against the action of the spring 43 by the cam 58 acting on roller 54 and the high portions of the claw cam surfaces 35a, 36a move away from the pin 41 toward the operating end K so that the claws move toward each other and their ends 35b, 36b overlie the operating end K of said arm 15. The cam surface 58a at this time has also acted on the cam follower 26 to retract the pointed end 21 of the plunger 20. The overhanging claw ends 35b, 36b then overlie the operating end K of arm 15 in a position to pick-up a washer C and unriveted eyelet E combination from a delivery means presently to be described, and remain in this position until the arm 15 has moved past its said six o'clock position. The cam 58 then drops away from the cam follower 54 to permit the spring to retract the slide 30 from its described outermost position and the overhanging claw ends 35b, 36b move toward the operating end K of arm 15 and act to press the washer and unriveted eyelet combination picked up by the claw ends 35b, 36b against the said operating end K of said arm. During this period of orbital travel the cam follower 26 rides off the cam surface 58a permitting the centering end 21 of plunger 20 to move outwardly of sleeve 18 into the tubular unriveted eyelet E of the washer-eyelet combination carried by the claw ends 35b, 36b and functions to center said combination with the headed end of the unriveted eyelet E overlying the outer end of sleeve 18. The cam 58 just prior to the arrival of the arm 15 in its aforesaid uniting or 12 o'clock position permits the spring 43 to move the slide

30 to its extreme innermost or retracted position at which time the cam pin 41 operating on the cam surfaces 35a, 36a of the claws 35, 36 to spread them apart to their described release position which is maintained until the operating end K of arm 15 passes its uppermost, uniting, or 12 o'clock position and reaches the starting point described. This operating cycle is repeated for each revolution of arm 15.

A second shaft 60 is rotatively supported in bearings 61 carried by frame parts 10. This shaft 60 extends in parallelism with the main drive shaft 11. A spur gear 63 of the same diameter and tooth number as the gear 14 is secured to this shaft 60 and meshes with the gear 14. The shaft 60 extends outwardly of the frame 10 and the other co-planar rotary arm 65 is secured to this outwardly extending portion of the shaft 60, for example by the locking bolt 66 (Fig. 15). This arm 65 constitutes the reinforcement carrying arm.

The operating end L of arm 65 is fitted with a riveting anvil member 66. This anvil member 66 has an upstanding nipple 67 for purposes to be presently described.

The arm 65 is equipped with a reciprocably movable slide member 68 which is mounted thereon in the same way as slide member 30 is mounted on the arm 15.

A pair of pick-up claws 70, 71 (Figs. 1 and 14-16 inclusive) are pivotally supported at 72, 73 from the slide member 68. Springs 74, 74a tend to rotate these claws 70, 71 toward each other about their pivotal supports 72, 73. These claws 70, 71 have oppositely facing cam surfaces 70a, 71a similar to the cam surfaces 35a, 36a and which co-operate with a cam pin 75 carried by the arm 65 and projecting through a slot 76 in the slide member 68.

The slide member 68 is normally urged by a spring 78 in a direction away from the operating end L of the arm 65. The ends of spring 78 are attached respectively to a pin member 79 fixed to the slide 68 and to a member 80 fixed to the arm 65.

The movement of the slide member 68 counter to the spring 78 is effected by crank levers 81, 82 both fixed to the shaft 63 which in turn is rotatably supported from a flange part 84 of the arm 65. The crank lever 81 is pivoted to the pin member 79 carried by a flange part 79a fixed to the slide member 68. The crank lever 82 has a cam follower or roller 85 secured rotatably thereto.

A cam 88 (Figs. 1, 3 and 6) is secured adjustably to the frame 10 about the shaft 60. The cam follower or roller 85 which serves to reciprocate the slide member 68 operates on the outer surface of this cam. This cam 88 functions to operate the cam roller 85 to effect reciprocal motion of the slide member 68 that is similar to that imparted by cam 58 to slide member 30 and for similar purposes.

When the slide member 68 is reciprocated under action of the spring 78 and movement of the cam follower 85 over the cam 88, the claws 70, 71 are spread apart to the releasing position thereof shown in Fig. 15 by the action of cam pin 75 on the cam surfaces 70a, 71a of the respective claws and permitted to move together to the limit permitted by the high portions of these cam surfaces when the cam pin 75 rides off the latter. The cam pin 75 is so positioned that the spreading apart of the claws 70, 71 occurs when the slide member 68 is moved away from the operating end of arm 65, while they are moved toward each other when the slide member 68 is moved toward the operating end of arm 65. The release posi-

tion of the claws shown in Fig. 15 is effected just prior to the arrival of the operating end L of the arm 65 at its uniting or lowermost or 6 o'clock position shown in Fig. 15, and is maintained until just after the said end L moves past said position. During the remainder of each revolution of said arm 65, the upper or claw ends 70b, 71b of the claws 70, 71 are positioned to overlie the operating end L of arm 65 on opposite sides of the nipple 67 for purposes presently to be described. When the operating end L of arm 65 moves toward its uppermost or 12 o'clock or pick-up position the cam 88 moves the slide 68 so that the claw ends 70b, 71b can pick up a reinforcement from a delivering means presently described. After said arm end L passes said last named pick-up position the slide 68 moves the claw ends 70b, 71b to press the picked up reinforcement R against the anvil 66 with the nipple 67 projecting through the perforation in said reinforcement R. The cycle of claw operations described occurs once for each revolution of the arm 65.

When the main drive shaft 11 is driven, the arms 15 and 65 rotate in synchronism. They are arranged to be co-planar and are so positioned on their respective shafts 11 and 60 that they become radially aligned with their respective operating ends in proximity as shown in Fig. 14 once during each revolution of the respective shafts 11 and 60. At this time, the paper web W to which the fasteners are to be applied lies between the two arm ends as seen diagrammatically in Fig. 19. Some time before the arms 15 and 65 arrive at this uniting position of Fig. 19, one must be loaded with a washer C and unriveted eyelet E and the other with a reinforcement member R. In the embodiment shown, the arm 65 is adapted to bring the reinforcement member R to the uniting position while the arm 15 is adapted to bring the combination of washer C and unriveted eyelet E to said uniting position. Separate means are provided for so loading the respective arms 15 and 65 once during each revolution of the latter.

The reinforcement, forming, feeding and loading means (Figs. 1-5 inclusive and 8-10 inclusive)

The reinforcement members R that are united with the washers or collars C and web W by the riveting of eyelets E, are in the embodiment shown, substantially square members each with a central perforation or hole. In this machine these members R are formed from strip material S as used. The strip material S which may come from a suitable source such as a roll or the like (not shown) is threaded around a curved end 90a of a guide 90 (Fig. 10), through a guideway 91 underlying the guide 90 and between a pair of rollers 92, 93, and thence through a continuation 60 of the guideway 91 to an outlet end of the latter.

The guideway 91 is formed in the upper surface of a plate 91a that is supported on the transverse frame 10a. The guide 90 overlies the guideway 91 and serves to retain the strip S within the latter. The roller 92 is supported on a stud shaft 94 which in turn is carried between a pair of brackets 95 (Fig. 5) mounted on the upper surface of the guide 90. The guide 90 is appropriately slotted at 96 (Fig. 10) so that the surface of the roller 92 which is appropriately roughened or knurled for purposes presently to be described may engage the upper surface of strip S.

The roller 93 is carried on a floating shaft 97 (Fig. 10) whose bearing blocks 98 are urged by springs 99 located within the supports 100 to

spring press the roller 93 through openings 101, 102 in the frame part 10a and plate 91a against the under surface of the strip S to maintain the said strip in frictional engagement with the roughened or knurled surface of the feed roller 92.

The feed roller 92 is rotated periodically step by step for part of a revolution sufficient to move the strip S a distance equal to the desired length of one of the reinforcements R. This step-by-step rotation is effected through the agency of a ratchet wheel 104 (Fig. 5) fixed to the stud shaft 94 and by a spring-actuated pawl 105 (Fig. 3) which is engageable with the teeth of the ratchet wheel 104. The pawl 105 is supported pivotally on a crank arm 106 which in turn is pivoted on the stub shaft 94. This crank arm 106 (Fig. 5) in turn is pivotally connected at 107 to a link 108 and the latter is pivotally attached at 108a to a coupling 109 which is secured to a connecting rod 110. The connecting rod 110 is connected to a coupling member 111 (Fig. 5) which in turn is pivotally connected at 112 to a coupling member 113 fixed to a crank lever 114. The crank lever 114 is pivotally supported at 115 to a fixed support 116 attached to a frame part 10c.

The crank lever 114 is operated by an eccentric or cam 117 (Figs. 1 and 5) which is fixed to the shaft 60 to rotate with the latter. The spring 118 maintains contact between the surface of cam 117 and the crank 114 so that once during each revolution of the shaft 60 the crank 114 is actuated by the cam 117 to depress crank 114 and cause the pawl 105 to advance the ratchet wheel 104 a single tooth, thereby advancing the strip S the length of one reinforcement R.

The strip S is perforated prior to the severance of the reinforcement R therefrom. To this end, the guide 90 (Figs. 10 and 7), the plate 91a and frame part 10a have aligned holes 120a, 120b, 120c. A punch 121 overlies these holes. This punch 121 may be moved downwardly through holes 120a and 120b and in such movement perforate the strip S and the punched-out part passes out through hole 120c.

The punch 121 is secured to the plunger block 122 which is movable reciprocally in the fixed guides 123, 124 that are attached to the frame-part 10a. A rod-like extension 125 of the block 122 projects upwardly of the latter through an opening 126 in a cross bar 127 which is fixed to the guides 123 and a spring 128 is positioned on the extension 125 above the cross bar 127 and a head or collar 130 fixed on said extension 125. This spring 128 normally tends to urge the block 122 upwardly so that the punch 121 lies above the surface of the strip S in the guideway 91, substantially as shown in Fig. 10. The downward or perforating motion of the punch 121 counter to the action of spring 128 is effected in a convenient manner.

In the embodiment shown (Figs. 1 and 10), a lever 132 is pivotally supported intermediate its ends at 133 from members 134 carried by the fixed brackets 95. A tined end 136 of this lever 132 engages the plunger block 122 with the tines extending on opposite sides of extension 125. A coupling member 137 is fixed at the opposite end 138 of lever 132. A coupling member 139 is pivoted at 140 to the coupling member 137 and a connecting rod 141 is attached to the coupling member 139. This connecting rod is connected to a coupling member 142. The latter is pivotally connected at 142a (Figs. 1 and 4) to a coupling member 143 (Figs. 1 and 4) which in turn is

secured to a forked slide member 144. The tines 145 of this slide member lie on opposite sides of the shaft 60 and serve to guide the motion of said slide member 144. A cam follower or roller 146 is rotatably supported by the slide member 144 on a shaft 147. An operating cam 148 is fixed to the shaft 60 in alignment with the cam follower or roller 146 so that rotation of shaft 60 causes the cam 148 to actuate the punch 121 in its perforating downward stroke once for each rotation of the shaft 60. This motion begins in the period of rotation of shaft 60 just prior to the time the arm 65 reaches its uniting or 6 o'clock position and is completed after the arm 65 passes such position but before its operating end reaches its pick-up or 12 o'clock position.

A shearing blade or knife 150 is secured to the punch plunger block 122 (Figs. 8 and 10). This knife operates through an opening in plate 90 over the outlet end of the guideway 91 in cooperation with the outlet end face of the plate 91a and serves to shear off the perforated portion of strip S that emerges from the outlet end of guideway 91. This sheared off portion is one of the reinforcements R that is to be applied to the moving web W of material.

Prior to severance of this reinforcement R from the strip S it is delivered onto a pair of receiving claws 152 (Figs. 1, 3, 9 and 10). These receiving claws are formed on a reciprocally movable block 153. The block 153 is guidedly supported between the fixed guides 154 which are carried by the guide 90 and is movable vertically and reciprocally through the opening 155 in said guide 90. A guide plunger 156 constituting an extension of the block 153 projects upwardly thereof through horizontal guide flanges 157, 158 of a fixed bracket member 159 secured to the guide plate 90. A spring 160 surrounds a portion of plunger 156 between the guide flange 157 and a fixed collar 161 mounted on the said plunger 156 (Fig. 9). This spring 160 tends normally to urge the block 153 upwardly to the limit permitted by the guide flange 157 which acts as a limit stop for such block 153 as well as a guide for the plunger 156. In this latter normal or unactuated position, the space 163 defined by the receiving claws 152 lies in alignment with the outlet end of guideway 91 so that the perforated end of strip S when fed forwardly and emerging from said guideway 91 is delivered directly into said space 163 and onto the claws 152. This feeding of the emerging perforated end of strip S onto the claws 152 is effected by the single step rotation of feed roller 92 and occurs while the punch is stationary and prior to the time that the punch plunger 122 is actuated to perforate the next following portion of the strip S. The feed roller 92 it will be remembered is operated intermittently only by the cam 117 and during its stationary or non-feeding period the punch 121 is actuated by its cam 148 to perforate the strip S and to return to non-punching position above strip S. Simultaneously with the perforating operation the knife 150 severs the previously perforated portion of strip S then extending outwardly of guideway 91 and whose end has been positioned on the claws 152. The beveled edge 150a of the knife 150 at this time acts as a wedge to center the severed portion which constitutes a perforated reinforcement R on the said claws 152 so that opposite sides of this reinforcement R overhang the side faces of the claws 152 in equal

amounts as seen in Fig. 10 for a purpose to be presently described.

The receiving claws 152 are co-planar with the rotating arm 65 so that the pick-up claws 70 and 71 of the arm 65 respectively can sweep past the outer side faces of the receiving claws 152 during rotation of said arm 65 to pick up the reinforcement R carried by them. In order to position the receiving claws 152 so that the reinforcement R carried thereby lies in the sweep circle of the overhanging ends 70b, 71b of the pick-up claws 70, 71, at the moment the latter sweep past said reinforcement bearing receiving claws 152, the plunger 156 bearing claw block 153 is movable vertically and downwardly in opposition to spring 160.

To this end, a cross bar 165 is secured to the plunger 156. A lever 166 (Figs. 1 and 5) is pivotally secured at 167 intermediate its ends to a fixed framepart 10d. One arm 166a of this lever is engageable with the cross bar 165. The opposite arm 166b of this lever has a coupling 167 attached thereto (Fig. 5). This coupling 167 is pivotally secured at 168 to a coupling 169. A connecting rod 170 is attached to this coupling 169 and to a coupling 171 which latter at 172 is pivotally joined to a crank lever 173. This crank lever 173 in turn is pivotally supported at 174 from a fixed support 175 carried by the framepart 10c. The crank lever 171 is substantially co-planar with the eccentric or cam 117 (Figs. 1 and 5) and with the crank lever 114. The spring 118 whose opposite ends are secured respectively to the crank levers 114 and 173 serves to maintain both said levers 114 and 173 in surface contact with said cam or eccentric 117. The latter thus serves the dual purpose of controlling the step by step operation of the feed roller 92 and the reciprocal vertical movement of the receiving claws 152. When the connecting rod 170 is moved upwardly by action of cam 117 on crank lever 114, the lever 166 is rotated so that its arm 166a engages the cross bar 165 (Fig. 1) and thereby moves the claw block 153 from the normal position shown in Fig. 9 downwardly in opposition to the action of spring 160 and in the direction of the arrow shown in Fig. 10 to bring the reinforcement receiving claws 152 to a position such that the reinforcement R then carried thereby lies in the sweep circle of the overhanging ends 70b, 71b of the pick-up claws 70, 71 of the arm 65. This occurs just prior to the time the arm 65 reaches its pick-up or 12 o'clock position. As the high part of the eccentric 117 recedes from engagement with crank lever 173 the spring 118 retracts moving rod 170 downwardly and thereby rotates lever 166 to lift its arm 166a clear of cross bar 165. Spring 160 then returns the claw block 153 to its normal position shown in Fig. 9. This occurs just after the arm 65 leaves its pick-up or 12 o'clock position. This cycle of operations just described occurs once during each revolution of shaft 60. Moreover, since the crank levers 114 and 173 lie on opposite sides of the shaft 60, the feed roller 92 and the claw block 153 are actuated at different times in each rotation of shaft 60 and cam concentric 117 so that the claw block 153 will remain stationary during feeding operation of the feed roller 92 with its receiving space 163 then opposite the outlet end of guideway 91.

The washer and unriveted eyelet combining and feeding unit

The washers C each have an unriveted eyelet E combined therewith by insertion of the uni-

headed end of the said eyelet E through the central perforation of the washer and said combination of washer and eyelet is fed to a delivery member for pick-up by the overhanging end 35b, 36b of the pick-up claws 35, 36 of the rotary arm 15. In the embodiment shown, the pick-up point lies at what may be termed the six o'clock position of the rotary arm 15. The mechanism for effecting the combination of washers C and unriveted eyelets E and the delivery of such combinations one by one to the said pick-up point will now be described:

Referring to the drawings and particularly to Figs. 1, 2, 3, 6 and 11-30 inclusive, 180 denotes a substantially horizontal table which is suitably supported from the frame members 10. This table member 180 consists of an upper plate member 181 and a lower plate member 182. The upper plate member 181 has an opening 183 in which a vertically extending tubular member 184 is positioned (Figs. 1, 11 and 13). This tubular member 184 is adapted to receive a pile P of the perforated washers C. The tubular member 184 extends only for a short length of the height of this pile P and in order to maintain the pile P in erect position above the tubular member 184, a guide string or wire 186 extends vertically through the perforations in the washers C within the pile P and is suitably supported from a portion of the frame (not shown). The string or wire 186 terminates within the tubular member 184 short of its lower end.

The lower plate member 182 has a longitudinally extending guideway 187 (Figs. 3, 11 and 13). This guideway 187 is arranged to underlie the tubular member 184. This guideway 187 has a depth that is only slightly greater than the thickness of a single washer C and a width only slightly larger than the diameter of said washer C so that only one of said washers C at a time may enter onto the guideway from the lower end of the pile P in tubular member 184.

A transfer slide member 190 (Figs. 11 and 13) is reciprocally movable in the guideway 187. The stroke of this slide member is such that its leading end 190a may move from an initial position shown in Fig. 13 behind the tubular member 184 to a position forwardly of the tubular member 184. In such movement the transfer slide member 190 engages the lowermost of the washers C in the pile P removing it from the said pile and pushes the so engaged washer C forwardly in the guideway 187 to a point at the opposite end of its stroke where the washer may be united with one of the unriveted eyelets E as will be presently described. During this motion the portion of the transfer slide member 190 behind its leading edge 190a underlies the pile P of washers and none of the latter may enter into the guideway 187.

Reciprocation of the transfer slide member 190 is effected as follows:

A slide block 191 is slidably supported on a pair of horizontally extending guide rails 192 (Figs. 2, 11 and 13), the latter being suitably supported from portions of the frame 10. This slide block 191 is secured as by bolt 193 to a guide block 194 which latter in turn is secured to the transfer slide member 190. The guide block 194 is movable in a longitudinally extending slot 195 which is provided in the lower plate 182 beneath guideway 187. The slide block 191 has oppositely extending pins 196 (Fig. 2). These pins 196 engage respectively in a slot 197 in each of the two cranks 198 (Figs. 2, 11 and 13). The latter are secured to a stub shaft 199 which is rotatably supported

between the fixed uprights 200 (Fig. 2) which are secured suitably for example to opposite sides of the horizontal plate 182.

A pair of cranks 202 (Figs. 1a and 2) are fixed to the stub shaft 199 and these cranks in turn are pivotally connected at 203 (Fig. 1a) to a coupling member 204. This coupling member 204 in turn has a connecting rod 205 attached to one end. The opposite end of the connecting rod 205 is secured to a coupling member 206 and the latter is secured pivotally at 206a to a cross bar 207 (Fig. 2). The cross bar 207 is slidably supported by the sleeves 208 from a pair of vertically extending guide rods or rails 209 which latter are suitably carried by the fixed supports 210 and 211. For convenience, the support 210 is fixed to the uprights 200 while the support 211 is conveniently fixed to the frame part 10a. Springs 212 are carried on the guide rails or rods 209 between the support 210 and the lower ends of the sleeves 208, serving to urge the sleeves and with them the cross bar 207 in a vertical direction away from the support 210.

Reciprocal motion of the cross bar 207 on its guide rails or rods 209 is effected by a cam or eccentric 214 (Fig. 2) which is fixed to the shaft 60. A cam follower 215 is rotatively supported on a stub shaft 213 which latter in turn is carried between a pair of bracket members 217 that are attached to the cross bar 207. Thus, for each revolution of the cam or eccentric 214, the cross bar 207 is moving from its uppermost position downwardly in opposition to the springs 212 to the limit determined by the largest radius of the eccentric 214 and then returned by the said springs to its initial position. In other words a single down and return stroke of the cross bar 207 occurs for each revolution of the shaft 60. This reciprocal motion of the cross bar 207 is translated into corresponding reciprocal motion of the transfer slide member 190 through the agency of the connecting rod 205, the cranks 202, the cranks 198, the slide block 191 and the guide block 194. The stroke of the cross bar 207 is, of course, sufficient to move the leading end 190a of the transfer slide member 190 from its starting position shown in Fig. 13 behind the tabular member 184 to its final forward position shown in Fig. 11 at which latter time the undermost washer C moved from pile P by the transfer slide member 190 within the guideway 187 lies at a combining point or position whereat an unriveted eyelet E is to be combined with it.

The eyelets E are delivered for combination with the washers C at the combining point just mentioned through an eyelet guide 220 (Figs. 2 and 3). The upper or receiving end of the eyelet guide 220 is arranged in conjunction with an eyelet containing hopper 221 which contains mechanism presently to be described for delivering the unriveted eyelets E to the guide 220. The hopper 221 and the eyelet guide 220 are secured to a bracket 222 which is pivotally supported at 223 to the frame parts 10.

For purposes presently to be described, the eyelet guide 220 is oscillated about the pivot point 223. To this end, a cam 224 is fixed to the main drive shaft 11 (Figs. 1 and 27). A forked guide member 225 has its tines 225a, 225b slidably engaging opposite sides of the main drive shaft 11 adjacent to the cam 224. The guide member 225 carries a rotatably supported cam follower 226 which engages the cam 224. Engagement between the cam follower 226 and the cam 224 is maintained by the action of gravity. However,

if desired, suitable spring means (not shown) may be utilized to maintain such engagement. The guide member 225 is pivotally connected at 227 (Fig. 27) to a connecting link 228 which latter in turn is pivotally connected at 229 to a coupling member 230 which is secured to the eyelet guide 220. Thus each rotation of the main drive shaft 11 serves through the agency of the cam 224, the guide member 225, the cam follower 226, connecting link 228 and coupling member 230 to effect a single reciprocating oscillation of the eyelet guide 220 about the pivot 223 as a center so that the delivery end 220a of said eyelet guide 220 may be appropriately moved to effect delivery one by one of the unriveted eyelets E for combination at the combining point with each successive of the washers C delivered to said point by said transfer slide member.

The delivery end 220a of the eyelet guide 220 is provided with a substantially V-shaped notch 231 (Figs. 20-25 inc.) and the unriveted eyelets E appear one by one at the apex of this notch with their unriveted ends facing downwardly. A resilient member or spring 232 is secured to the eyelet guide 220 near its end 220a. This spring 232 has a portion 232a that is normally positioned to engage under the headed end of the unriveted eyelet E appearing at the notch as shown in Figs. 20 and 21 to prevent the said eyelet E from falling out of the eyelet guide 220. This portion 232a of the spring is adapted to yield sufficiently to permit removal of the said unriveted eyelet E from the notch 231 as will be presently described.

The eyelet guide 220 is adapted to deliver the unriveted eyelets E so that their unheaded ends when they arrive at the notch 231 are lowermost, and the spring portion 232a engages under the headed end of each of the eyelets as it reaches said notch 231.

At the combining point of the washers and the unriveted eyelets, a pair of transversely movable spring actuated jaws 235, 236 are positioned, suitable lateral recesses 237 and 238 being provided for this purpose in the upper table plate 181. The adjacent faces 235a, 236a of these jaws 235, 236 are oppositely slanted so that when the jaws are in abutment a V-shaped recess 239 is formed by them. The apex of the recess overlies the center of the guideway 187 for a purpose to be presently described. The springs 240, 241 normally urge the respective jaws 235, 236 toward each other.

A reciprocally movable plunger member 250 is supported in alignment with the V-shape notch 239 and above the latter. This plunger member 250 has a portion 251 whose diameter is so ad-measured to permit it to be inserted through the unriveted hollow eyelets E from their headed ends. The end 251a of this portion may be pointed to facilitate such entry into the hollow unriveted eyelets E. The plunger 250 is carried by the cross arm 252 (Fig. 26) and the latter in turn is slidably movable on the guide rails 253 which are supported vertically from a part 254 (Figs. 1, 20, 22 and 24) carried by the upper plate 181. The springs 255 which are mounted on the guide rails 253 between the cross arm 252 and the part 254 tend normally to urge the cross arm 252 and with it the plunger member 250 upwardly so that the pointed end 251a lies a distance above the part 254.

Reciprocal motion of the cross arm 252 on the guide rails 253 and consequently reciprocal motion of the plunger 250 is effected by a cam 257

(Figs. 1 and 26). This cam is fixed to the main drive shaft 11 and rotates with the latter. A cam follower 258 is rotatably carried on a shaft 259 on which it is carried by the forked guides 260, and the tines 260a, 260b of these guides extend on opposite sides of the shaft 11 and function to guide the vertical motion of the guides 260. The latter are secured to the cross arm 252. In consequence, the springs 255 maintain the cam follower 258 in engagement with the cam 257. Rotation of the cam 257 with the shaft 11 thereby effects reciprocal motion of the plunger member 250. For each rotation of the shaft 11, the plunger 250 is moved once from its uppermost or retracted position shown in Fig. 21 to its lowermost position shown in Fig. 23 at which time it has removed an unriveted eyelet E from outlet end 220a of the eyelet guide 220 and inserted it through the porforation of the underlying washer C.

The sequence of operations effected respectively by the cam 257 which operates the plunger 250 and the cam 224 which effects reciprocal oscillatory motion of the eyelet guide 220 is as follows:

Just after the leading end 190a of transfer slide member 190 has reached the limit of its transferring stroke as shown in Fig. 11 and has pushed one of the washers C below the jaw members 235, 236 with the central perforation of the washer in alignment with the end 251a with the plunger 250, the latter lies in its uppermost position as shown in Fig. 21. At this time the cam 224 has been rotated to such a position by the shaft 11 that the apex of the notch 231 in the delivery end 220a of the eyelet guide 220 lies substantially below the pointed end 251a of the plunger 250, with an unriveted eyelet E engaged by the spring end 232a in axial alignment with the said pointed end 251a.

As the shaft 11 continues to rotate the cam follower 226 operating on the cam 225 moves on a portion thereof which fails to impart any motion to the eyelet guide 220. However, the plunger operating cam follower 258 begins to move on a part of the cam 257 which moves the plunger 251 in a downward direction for a distance sufficient for the pointed end 251a and the reduced portion 251 to be inserted into the hollow eyelet E then engaged by the spring end 232a. As soon as this occurs the eyelet guide oscillating cam 225 begins to operate the eyelet guide to move its delivery end 220a clear of the plunger 251 as shown in Fig. 25. Such motion because of the previous insertion of the plunger end 251a into the eyelet E causes the latter to be pulled out of the V-notch 231 against the action of the spring end 232a. The plunger member 251 then continues downwardly carrying with it the eyelet E and moving it first into the V-shaped notch 239 provided by the faces 235a, 235b of the jaws 235, 236 and then further through these jaws which move apart against the opposition of their springs 240, 241 until the unheaded end of the eyelet passes through the perforation in the collar C underlying the jaws 235, 236 and until the head of the eyelet clears the lower edges of the said jaws. When such clearing occurs the jaws 235, 236 spring together sufficiently as shown in Fig. 23 to overlie the headed end of the eyelet E which has been inserted into the collar C so that the retractive movement of plunger 251 which now begins does not carry with it the so inserted eyelet E. After insertion of the end 251 of the plunger 250 the eyelet guide operating cam 224 func-

tions to move the delivery end 220a of the eyelet guide clear of the path of travel of the plunger 251 and its associated parts. When the plunger operating cam 257 returns in its upward stroke to its initial position as shown in Fig. 21, the eyelet guide operating cam 224 has again operated to permit restoration of the delivery end 220a of the eyelet guide 220 to the position shown in Fig. 21. This cycle of operations occurs once during each revolution of the main drive shaft 11, and is repeated for each such revolution.

After an unriveted eyelet E has been inserted or combined with a washer C underlying the eyelet inserting plunger 251 as just described and after the latter has been moved out of the so inserted eyelet E, the washer and inserted unriveted eyelet combination so made must be transferred to a receiving means 270 in which it may be positioned for pick-up by overhanging ends 35b, 36b of the pick-up claws 35, 36 of the rotary arm 15. This receiving means 270 (Figs. 6, 11 and 13) comprises a block 271 which is movable vertically and reciprocally at the delivery end of the guideway 187. This block 271 has a transversely extending open ended slot 272 (Fig. 6) which in the receiving or lowermost position of the block 271 is aligned with the guideway 187. The block 271 is recessed at 273 below the slot 272 for an amount sufficient to receive the unheaded end of the eyelet E of the unriveted eyelet-washer combination moved toward it from the point of combination of such unriveted eyelet and washer.

The mechanism for transferring each combined washer and unriveted eyelet in turn to the receiving jaw 270 comprises a pusher pin 278 (Figs. 11-13) that is movable reciprocally in the longitudinal direction of the plate members 181, 182 and normally moves in the slot 195 of the table plate member projecting a sufficient distance therethrough from the under side of said plate member 182 to engage behind each washer C after the latter has been combined with an unriveted eyelet E as hereinbefore described. This pin is secured to a block 279 and the latter in turn is connected to a rod 280 which in turn is secured pivotally at 281 (Fig. 11) to the slide block 191. By this arrangement, the movement of the pusher or transfer pin 278 is controlled by the same cam or eccentric 214 which reciprocates the slide block 191 through the cranks 198. In other words, the transfer pusher pin 278 and the transfer slide 190 are operated from a common controlling cam 214 and are moved simultaneously.

In the movement of the transfer pin or plunger 278 from its final position shown in Fig. 11 rearwardly to its starting position shown in Fig. 13, it is necessary for the pin or pusher 278 to be depressed as it passes below the point of combination of washers C and eyelets E, that is, as it passes below the eyelet and washer combining mechanism described above. To this end, a cam wedge 285 (Figs. 11-13) is pivotally supported intermediate its ends at 286 from a fixed bracket 287 which is secured to the member plate 182. The wedge 285 lies in the path of travel of a laterally extending pin 279a fixed to the block 279 so that as the block 279 is moved in its retraction stroke, this pin 279a engages the under face of the wedge 285 which widens in the direction of the retraction stroke and such engagement is shown in Fig. 12. This engagement causes the block 279 carrying the pusher

pin 278 to be rotated sufficiently about its pivot 281 to permit the pin 278 to clear the pointed end 251a of the eyelet inserting plunger 251. The cam wedge 285 is so admeasured in length that the laterally extending pin 279a rides off the lower face of the same wedge 285 just prior to the time that the block 271 reaches its rear-most position as shown in Fig. 13. At this time, the spring 289 which is fixed at one end of slide block 191 and whose other end engages the pivoted rod 290 returns or restores the pusher pin 278 to its original level at which time it lies behind rear edge of the washer and bearing an inserted eyelet E as seen in Fig. 13. On the next forward stroke of the pusher pin 278, the pin 279a rides over the top face of the cam wedge 285 so that the pusher pin 278 remains at its high level shown in Fig. 13 and feeds the combined washer C and unriveted eyelet E forwardly in the guideway 181 and delivers it into the slot 272 of the receiving jaw block 271.

When a combined washer and eyelet have been delivered into the slot 272 of the block 271, it is necessary to move the latter vertically to raise the washer and unriveted eyelet combination carried thereby to a level wherein it will be picked up by overhanging ends 35b, 36b of the claws 35, 36 of the arm 15. To this end, the block 271 is secured to a slide rod 295 that is guidedly supported in laterally extending flanges 296, 297 which extend from a suitable bracket member 298 carried by the upper plate member 181. The lateral flange 296 serves as a limit stop for the lower end of jaw block 271 and when the latter rests upon it the jaw slot 272 is in alignment with the outlet end of the guideway 181. The plate member 181 is perforated at 299 to permit vertical movement of the jaw block 271 therethrough. A movement in the upward direction is effected by the plunger operating cam 251.

To this end, the guide 260 (Fig. 26) carries a laterally extending pin 300. A coupling member 301 (Fig. 1) is pivotally secured to this pin and one end of a connecting rod 302 is secured to the coupling member 301. The opposite end of the connecting end of the rod is pivotally secured at 303 (Fig. 1) to a coupling member 304. The latter in turn is secured to an end of a lever 305. This lever 305 is pivotally supported intermediate its end at 306 from a fixed support 307 conveniently attached to the upper horizontal plate 181. The free end of the lever 305 is movable into an engagement with a cross bar 308 that is fixed to extend laterally from the guide rod 295 and the jaw block 271. A suitable spring 309 positioned on the rod 295 between a fixed collar 310 and the lateral flange 297 normally urges the rod 295 and its jaw block 271 downwardly into position shown in Fig. 11. Once during each rotation of the cam 257 through the agency of the connecting rod 302, lever 305 and cross bar 308, the jaw block 271 is lifted from its position shown in Fig. 11 to the raised position shown in Fig. 1 at which time the jaw slot 272 lies above the level horizontal top plate 181 and in the sweep stroke of the overhanging ends 35b, 36b of pick-up claws 35, 36 of the arm 15 which move past the said block 271 on opposite sides thereof and pick up the combined washer C and unriveted eyelet E then lying in the slot 272. The cam 251 is so arranged on the drive shaft 11 that the block 271 reaches its uppermost or pick-up position just prior to the moment when the arm 15 arrives at the pick-up position of its stroke.

This pick-up position, in the embodiment shown, may conveniently be described as the 6 o'clock position of the arm 15.

The unriveted eyelets E are initially dumped haphazardly into the hopper 221. It has a removable cover plate 315 for such purposes. The upper or receiving end 220b of the eyelet guide 220 terminates within the hopper along one wall thereof as shown in Figs. 28 and 29. This terminal end 220b has a substantially V-shaped notch 220c and this notch lies in spaced relation from a block 316 which also is carried on the same face of the hopper 221. The recess 317 of this block overlies the notch 220c. The block 316 is provided on its front face with a plurality of vertically extending grooves 318. A brush member 319 is supported within the hopper on a transversely extending shaft 320 journaled in opposite side walls of the hopper 221. This brush member has sets of radially extending bristles 319a which are admeasured in radial length to engage the lower curved wall 221a of the hopper and when the brush is rotated clockwise, as seen in Fig. 28, the bristles 319a serve to sweep eyelets which lie haphazardly in the hopper 221 upwardly into the recess 317 of the block 316 from which when properly aligned they drop into the receiving notch 220c of the eyelet guide 220. The grooves 318 in the block 316 permit the ends of some of the bristles during rotation of the brush to enter into the recess 317 and agitate eyelets E in said recess and orient them at random and sufficiently frequently so that enough eyelets E will be arranged therein with respect to the notch 220c of the eyelet guide 220 to fall into the latter in proper position so that they will pass downwardly through the eyelet guide 220 to its delivery end 220a in the position shown in Figs. 21, 23, 25 and in Fig. 30. The shaft 320 is suitably driven by a sprocket wheel 325 shown in Fig. 3 which is fixed to a portion of the shaft 320 that extends externally of the hopper 221. This sprocket may be coupled through a chain 326 to any convenient source of motive power as sprocket 321. Any other conventional means for feeding the eyelets to the eyelet guide 220 may be utilized.

In the embodiment shown, the hopper is mounted on the pivoted bracket 222 that supports the eyelet guide 220 so that it is agitated to some extent by the reciprocal oscillatory motion imparted to the eyelet guide 220 through the agency of the cam 224 as is previously described. This aids in proper delivery of the unriveted eyelets E to the guide 220.

Means (not shown) are provided for moving the web W in timed relation to the eyelet applying means and the web is guided suitably in a fixed member 350 carried by the frame. This guide has a slot 351 through which the web W passes. A smoothing out member 352 having spring fingers 353 is adjustably mounted on the member 350 so that the spring fingers press against the web W from opposite sides to prevent lateral slip of the web in the guide slot 351.

The operation of the machine

The general operation of the machine is briefly, as follows:

The main drive shaft 11 is driven by coupling of its sprocket wheel 13 to a suitable source of motive power (not shown). The rotation of this main drive shaft 11 initiates all the movements of the various parts of the machine and the various cams control the necessary sequential

actions of the parts so that the timing of operation of particular movable members that serve to feed reinforcement strap S, perforate it, sever it into successive reinforcements R, deliver them in turn to the receiving claw 152 for pick-up by the pick-up claws 70, 71 of the arm 65 and the timing of operation of movable parts that serve to transfer the washers C one by one from the pile P to the combining point where they are each combined in turn with an unriveted eyelet E and subsequently transferred to the slots 272 of the receiving jaw 270 for pick-up by the pick-up claws 35, 36 of the rotary arm 15, all are arranged to occur at proper periods during each single revolution of the main drive shaft 11. This timing is effected so that each time the arm 65 reaches the uppermost or 12 o'clock position of its orbit, and the arm 15 reaches the lowermost or 6 o'clock position of its orbit the respective pick-up claws on these arms can engage a properly positioned reinforcement and a combined washer and eyelet.

As the arms 15 and 65 continue in their rotation from their said lowermost and uppermost positions just described, they carry with them respectively the combined washer and eyelet picked up from the receiving jaw 270 and the reinforcement R picked up from the receiving claws 152. The nipple 67 on the anvil member 66 then extends through the perforation in the reinforcement R. As movement continues the slide member 68 which carries the pick-up claws 70, 71 is moved rearwardly from the operating end of the arm 65 by the action of the cam 88 on the cam follower 85 so that the overhanging ends of the pick-up claws 70, 71 serve to press the reinforcement member R lightly against the anvil 66. This action together with the nipple 67 retains the reinforcement R on the operating end of the arm 65.

A similar action occurs simultaneously with respect to the washer and eyelet combination picked up by the claws 35, 36 of arm 15. At the moment the operating end of the arm 15 sweeps past the elevated receiving jaw 270 its claws 35, 36 engage behind the washer-eyelet combination carried in the slot 272. At this moment, the slide 30 has been moved outwardly toward the operating end of the arm 15 by the action of the cam 58 on the cam follower 54 so that the portions 35b, 36b of the claws 35, 36 overhanging the operating end K of said arm 15 are spaced from said operating end. Immediately after the operating arm 15 sweeps past the receiving jaw 270 the cam follower 54 rides off a high portion of the cam 58 and this causes the spring 43 to move the slide 30 in retractive stroke in a direction away from the operating end K of arm 15 so that the overhanging portions 35b, 36b of the jaws 35, 36 move toward the operating end K of the arm 15 and clamp the washer and eyelet combination that they have picked up against said operating end of the arm 15. The eyelet E is substantially centered and overlies the pin 21 which is movable reciprocally within the sleeve 18. During this period the pointed end 21 of the plunger 20 has been maintained in a retracted position by action of the cam 58a on the cam follower 26. Substantially at the same time that the cam follower 54 rides off the high point of the cam 58 to effect the retractive stroke of the slide 30, the cam follower 26 rides off the cam surface 58a and permits the spring 22 to move the plunger 20 forwardly so that its pointed end 21 projects outwardly of the sleeve 18 and enters

the eyelet E of the washer-eyelet combination then carried on the operating end of the arm 15 by the pick-up jaws 35, 36. This entry of the pointed end of the plunger 20 into the eyelet E serves to accurately center washer-eyelet combination over the end of this sleeve 18. It will be noted that at this time the headed end of the eyelet E of the washer-eyelet combination rests against the upper end of the sleeve 18.

10 The arms 15 and 65 carrying respectively a reinforcement R and a washer-eyelet combination continue rotation with their respective shafts 11 and 60 at equal speed through the agency of the meshing gears 14 and 63. The respective arms 15 and 65 are so fixed on the respective shafts 11 and 60 that they approach respectively the uppermost position of the orbital path of the operating end of the arm 15 and the lowermost orbital position of the operating end of the arm 65 at the same speed and reach these positions simultaneously at which time the two arms are in vertical alignment as shown in Figs. 14 to 16 inclusive with their operating ends K and L adjacent to each other.

25 The traveling web of material W with which the washers C, unriveted eyelets E and reinforcements R are to be combined is suitably guided so that it lies between the said operating ends of the arms 15 and 65 when they are in the positions

30 just described. In the embodiment shown, the operating end K of the arm 15 approaches the traveling web W from the under face of the latter while the operating end L of the arm 65 approaches the said web from the opposite or upper

35 face thereof. As the arms approach the combining position just described, by the return of the claws to their original positions under the influence of the spring 43, said pick-up claws 35, 36 and 70, 71 are moved by pin 41 to release positions

40 previously described. When the arms reach the said combining position, the unheaded end of the unriveted eyelet E lies uppermost on the operating end of the arm 15 and pierces the web W and projects through it and the perforated

45 reinforcement R carried by the operating end of the arm 65 is positioned on it. The unheaded end of the eyelet E further slides over the member 67 and into engagement with the surface of the anvil member 66 which then functions to

50 be over the unheaded end of the eyelet end thereby to rivet the reinforcement R and the collar C to the web W on opposite sides thereof.

Just prior to the completion of the riveting action described, the respective cams 58 and 88

55 actuate their respective cam followers 54 and 85 to move their respective slides 30 and 68 in directions away from the respective operating ends of these arms so that the cam pins 41 and 75

60 above the pick-up claws 35, 36 and 70a, 71a of pick-up claws 70, 71 to spread these jaws apart to their release positions as shown in Fig. 15 so that the latter clear the operating ends K and L of the respective arms 15 and 65. The spread

65 of the respective claws at this time completely clears them from the washer and eyelet combination as well as the reinforcement R so that there is no interference with the riveting over of the unheaded end of the eyelet E by the action

70 of the anvil 66.

The web E to which the washer C and reinforcement R have been riveted by the eyelet E as just described, continues to move substantially tangentially of the orbits of the operating ends 75 K and L of the arms 15 and 65 and the joined

parts move away from the riveting point. The arms 15 and 65 continue in their rotation with their respective shafts 11 and 60 and eventually reach their respective pick-up positions for repetition of the cycle just described.

During the movement of the arms 15 and 65 from the uniting or riveting position to their respective pick-up positions, the respective pick-up claws on these arms are restored to their original positions by appropriate movement of the slides 30 and 68 under the action of the respective cams 58 and 88. At the same time during this period of motion of the said arms 15 and 65 the various parts of the machine that function to feed a new reinforcement member R to the receiving claw 152 are effected, and simultaneously the various parts of the machine that function to transfer a washer C from the pile P to the point of combination with an unheaded eyelet E and subsequent transfer of the combined new washer and eyelet E to the receiving slot 272 of the jaw 270 are operated. The claw 152 and also the receiving slot 272 bearing respectively the newly delivered reinforcement R and a newly delivered combined washer and eyelet are then positioned so that at the commencement of the next cycle of operation they may be picked up by the respective pick-up claws on the respective operating arms 15 and 65 for ultimate combination with the traveling web.

It is to be understood of course that the web W preferably moves continuously and that its surface speed is substantially equal to the surface speed of the operating ends of the respective arms 15 and 65. Likewise, the drive shaft 11 is continuously rotated and each revolution of the shaft 11 effects the union of a collar C, eyelet E and reinforcement R with the traveling web.

Subsequently the web W bearing the attached collars, eyelets and reinforcements at spaced apart points may be handled by suitable machines or otherwise to form bags or envelopes of the type shown partially in Fig. 31. Therein a fastener consisting of the washer or collar C on the external face of the upper lap Y of the bag body Z and an underlying reinforcement R on the under face of the upper lap Y are joined by the riveted over eyelet E passing through said lap Y is shown. It is to be understood, however, that bags or envelopes of different kinds than that shown in Fig. 31 may be prepared from web W to which such fasteners have been attached by the machine herein described.

While a preferred embodiment machine has been described herein, it is to be understood that various changes in structural detail may be made and are contemplated. There are no intentions therefore of limitation to the exact details shown and described.

What is claimed is:

1. A machine of the character described comprising co-planar rotary arms, means on one of said arms for retaining a washer-eyelet combination thereon, means on the other of said arms for retaining a perforated reinforcement thereon, means for rotating the said arms at synchronous speed to bring the washer-eyelet combination and the reinforcement into an aligned position on opposite sides of a moving web, means on said arms for then uniting the reinforcement with the washer-eyelet combination and the web, and means for operating the said two retaining means to release the said rein-

forcement and said washer-eyelet combination just prior to their union with said web.

2. A machine of the character described comprising a pair of co-planar rotary uniting and riveting members, means on one of said members for picking up and carrying a washer and unriveted eyelet combination, means for combining washers and unriveted eyelets and delivering such combinations one by one to a position for pick-up by said picking up and carrying means, means on the other of said co-planar members for picking up and carrying a perforated reinforcement, means for forming perforated reinforcement members from a strip of reinforcement material and for delivering such perforated reinforcements one by one for pick-up by said second-named picking up and carrying means, means for rotating said co-planar members to bring the washer and unriveted eyelet combination and the perforated reinforcement carried by the respective of the picking up and carrying means of said co-planar rotary members into alignment on opposite sides of a moving web, means on said co-planar members then serving to project a part of the unriveted eyelet of the carried washer and unriveted eyelet combination through the web and to mount the carried perforated reinforcement on said part and to rivet over the end of said part, and means for operating each of the first-named three means in timed relationship to effect operation during periods of each revolution of said rotary co-planar members other than the period when said two picking up and carrying means are picking up respectively a reinforcement and a washer and unriveted eyelet combination, and the period when said carried reinforcement and said carried washer and unriveted eyelet combination are being united with said web.
3. A machine for applying fasteners of the type consisting of a washer and reinforcement member secured on opposite sides of a sheet of material by a riveted eyelet comprising a pair of co-planar rotary uniting and riveting members, claw means on one of said members for retaining a washer and unriveted eyelet combination, claw means on the other of said arms for retaining a perforated reinforcement, means for rotating the said co-planar members to bring the washer-unriveted eyelet combination and the perforated reinforcement into alignment on opposite sides of said sheet of material, means on said co-planar members then serving to project an unheaded end of the unriveted eyelet of said washer-eyelet combination through said sheet and to mount said reinforcement on said end and to rivet over the latter, means for spreading apart said claw means to release said washer-eyelet combination and said reinforcement just prior to their union with said sheet, and cam means for moving said claw means in timed relation with operation of said rotary members and in relationship to said spreading means to effect said spreading apart of said claw means.
4. A machine for applying a fastener to a moving web of material comprising a rotary member, pick-up means on said member, means for delivering a washer combined with an eyelet having a headed end and an unheaded end to a position for engagement by said pick-up means, a second rotary member, pick-up means on said last-named member, means for delivering a perforated reinforcement member to a position for engagement by said last-named pick-up means, means for rotating said two members, and

to bring said combined washer and eyelet and said reinforcement carried by the respective pick-up means into alignment upon opposite sides of said moving web, and means on said rotary members then serving to project the unheaded end of said eyelet through said web and through the perforation in said reinforcement member and to rivet over said unheaded end of said eyelet.

5. A machine for applying fasteners to a moving web of material comprising a rotary member, pick-up means on said member, means for delivering washers each combined with an eyelet having a headed end and an unheaded end successively to a position for engagement successively by said pick-up means, a second rotary member, pick-up means on said last-named member, means for delivering perforated reinforcements successively to a position for engagement successively by said last-named pick-up means, means for rotating said two members and to bring a washer and eyelet combination and a reinforcement carried by the respective pick-up means into alignment on opposite sides of said web once during each revolution of said rotary members, and means on said rotary members then serving to mount the perforated reinforcement on said eyelet and then to rivet over the unheaded end of the latter.

6. A machine for applying fasteners of the washer and reinforcement type to a moving web of material comprising a rotary member, claw means on said rotary member, a receiving member for perforated reinforcements, means for forming and delivering said perforated reinforcements one by one to said receiving member, means for positioning said receiving member so that said claw means may remove each perforated reinforcement delivered to said receiving member, a second rotary member, claw means on said second rotary member, a receiving member for a combined washer and unriveted eyelet, means for combining washers and unriveted eyelets and for delivering such combinations one by one to said second-named receiving member, means for positioning said second-named receiving member so that said second-named claw means may remove each such combination delivered to said second-named receiving member, means for rotating said two rotary members to bring a reinforcement and one of said combinations into alignment on opposite sides of said moving web, and means on said rotary members then serving to mount the perforated reinforcement on said unriveted eyelet and to rivet over the latter to secure the reinforcement thereto and to said washer on the side of the web opposite to that of said washer.

7. A machine for applying to a moving web of sheet material fasteners of the type consisting of a washer and reinforcement secured on opposite sides of the sheet by a riveted eyelet comprising a pair of co-planar rotary uniting and riveting members, synchronously driven shafts on each of which one of said co-planar members is secured, means for driving said shafts, claw means on one of said co-planar members for retaining a reinforcement, claw means on the other of said co-planar members for retaining a washer and unriveted eyelet combination, said two carrying means being adapted to bring a reinforcement and a washer and unriveted eyelet combination into alignment on opposite sides of said moving web in each revolution of said co-planar members, means on said co-planar members then

serving to project an unheaded end of the unriveted eyelet of the washer and eyelet combination through the moving sheet and to mount said reinforcement thereon and to then rivet over the said unheaded end, means for spreading apart said claw means to release said washer-eyelet combination and said reinforcement just prior to their union with said sheet, and cam means for moving said claw means in timed relation with operation of said rotary members and in relationship to said spreading means to effect said spreading apart of said claw means.

8. A machine for applying to a moving web of sheet material fasteners of the type consisting of a washer and a reinforcement secured on opposite sides of the sheet by a riveted eyelet comprising a pair of co-planar rotary uniting and riveting members positioned on opposite sides of said moving web, means for rotating said co-planar members in synchronism, means on one of said co-planar members for picking up and carrying a reinforcement, means on the other of said co-planar members for picking up and carrying a washer and unriveted eyelet combination, means for forming said reinforcement and delivering it for pick up by the first-named picking up and carrying means, means for preparing said washer and unriveted eyelet combination and delivering it for pick up by the second-named picking up and carrying means, said two picking up and carrying means being adapted to bring a reinforcement and a washer and unriveted eyelet combination into alignment on opposite sides of said moving web in each revolution of said co-planar members, means on said co-planar members then serving to project an unheaded end of the unriveted eyelet of the washer and eyelet combination through the moving sheet and to mount said reinforcement thereon and to then rivet over the said unheaded end, and means for operating said reinforcement forming and delivering means and said washer and unriveted eyelet combination preparing and delivering means in timed relationship relative to the rotation of said co-planar members.

9. A machine of the character described comprising means for combining washers with eyelets each having a headed and an unheaded end, a receiving member, means for delivering each eyelet-washer combination in turn to said receiving member, orbitally travelling means for picking up in turn each eyelet-washer combination delivered to said receiving member, means for moving said receiving member each time it bears an eyelet-washer combination to a position whereat the latter may be picked up by said picking up means, and means for adjusting the timing of the several means effecting delivery of such eyelet-washer combinations to said receiving member and said positioning of the latter to a period of the orbital travel of said picking up means that is prior to its arrival at said position where the eyelet-washer combination is removed thereby from said receiving member.

10. A machine of the character described comprising a pair of co-planar uniting and riveting members, means for rotating said members, picking up and carrying means on one of said rotary co-planar members, means for supporting a pile of washers, means for delivering such washers one by one from said pile for combination of each with an eyelet having a headed and an unheaded end, means for delivering such eyelets one by one to a position for such combination, means then

operative to insert the unheaded end of each successive eyelet into each successive washer delivered to said position, and means for transferring each combination of washer and inserted eyelet to a position for pick-up by said picking up and carrying means.

11. A machine of the character described comprising a pair of co-planar rotary uniting and riveting arms, means for rotating said arms, claw means on one of said arms, a receiving member, means for delivering to said receiving member successive combinations of a washer and an eyelet, means for moving said receiving member after each delivery thereto of one of said combinations to position the delivered combination for pick-up by said claw means, and means for then operating said claw means to retain the combination picked up thereby for a prescribed portion of a revolution of that one of said arms carrying said claw means and for operating said claw means on completion of such prescribed period of a revolution to release the combination retained thereby.

12. A machine of the character described comprising a pair of co-planar rotary uniting and riveting members, means for rotating said members, means for severing reinforcement members from a strip, means for perforating such reinforcement members prior to their severance from said strip, pick-up means on one of said co-planar members, and means for delivering the severed and perforated reinforcement members one at a time to a position for pick-up by said pick-up means.

13. A machine of the character described comprising means for feeding a strip of reinforcement material step by step, means for severing a reinforcement from said strip, means for perforating each reinforcement, a receiving member, means for delivering each reinforcement in turn to said receiving member, orbitally traveling means for picking up in turn each reinforcement delivered to said receiving member, means for moving said receiving member bearing a reinforcement to a position where the latter may be picked up by said picking-up means and removed from said receiving member, and means for adjusting the timing of the several means effecting feed of said strip, severance of reinforcements therefrom, perforation of said reinforcements, delivery of the latter to said receiving means and said positioning of the latter to a period of the orbital travel of said picking-up means prior to its arrival at said position where a reinforcement is removed thereby from said receiving means.

14. A machine of the character described comprising a pair of co-planar rotary uniting and riveting arms, means for rotating said arms, means for severing reinforcements from a strip, means for perforating each of such reinforcements prior to its severance from said strip, claw means on one of said co-planar arms, a receiving member into which said perforated reinforcements are delivered one by one, means for moving said receiving member after a reinforcement has been delivered thereto to a position for pick-up of said delivered reinforcement therefrom by said claw means, and means for then operating said claw means to retain the reinforcement picked up thereby for a prescribed portion of a revolution of that one of said co-planar arms

carrying said claw means and for operating said claw means upon completion of such prescribed period of a revolution to release the reinforcement retained thereby.

15. A machine of the character described comprising two co-planar rotary members, means for guiding a moving web of material between the two members, claw means on one of said members for retaining a washer-eyelet combination thereon, claw means on the other of said members for retaining a perforated reinforcement thereon, means for rotating said members at synchronous speed to bring the washer-eyelet combination and the reinforcement into aligned positions on opposite sides of said web, means on said members for then uniting said reinforcement with said washer-eyelet combination and said web, means for spreading apart said claw means in timed relationship to the rotation of said rotary members, and cam means for moving said claw means relative to said spreading apart means.

16. A device as per claim 15, wherein said co-planar rotary members are arms having operating ends that engage said web only at that period of their revolutions when a reinforcement is being united with a washer-eyelet combination and said web.

17. A device as per claim 15, wherein said cam means are positioned to move said claw means relative to said spreading apart means to release said reinforcement and said washer-eyelet combination from their respective retaining means just prior to the uniting of said reinforcement with said washer-eyelet combination and said web.

18. A machine for applying fasteners to a moving web of material comprising a first rotary arm, a first set of claw members carried by said first arm, means for delivering a washer combined with an eyelet to aid first set of claw members, a second rotary arm, a second set of claw members carried by said second arm, means for delivering a perforated reinforcement member to said second set of claw members, means for rotating said arms so that the latter engage said web simultaneously once during each of their revolutions and while carrying a washer-eyelet combination and a reinforcement member, said arms then being so disposed that an unheaded end of said eyelet is forced through said web and the said reinforcement member is mounted thereon and then the unheaded end is bent over by the second of said arms to fasten said washer and reinforcement to opposite sides of said web, independent means for spreading apart each set of claw members in timed relationship to the rotation of the rotary members, and independent cam means for moving each set of claw members relative to its spreading apart means.
